UNITED STATES PATENT OFFICE

WILLIAM H. PEADEN, OF OKLAHOMA CITY, OKLAHOMA, ASSIGNOR OF ONE-FOURTH
TO W. Y. TENNYSON, OF SALINA, OKLAHOMA

COMBINATION SHADE AND AWNING

Application filed July 17, 1926. Serial No. 123,176.

This invention relates to window shades for the window openings of automobiles and the general object of the invention is to provide a shade which may be adjusted so as to extend downward and outward on the exterior of the car like an awning and which may be adjusted to any desired angle and to secure any desired extension of the flexible curtain or shade proper.

A further object is to provide means whereby the window shade and the mechanism for holding it may be turned upward within the automobile to permit the sliding glass of the window to close or which may be adjusted so as to draw the curtain or shade proper partly or entirely downward over the window.

Still another object is to provide an attachment in the form of a frame or bow which may be readily mounted upon the frame of the window and connected with the usual curtain to secure the resilience heretofore referred to, the bow of the frame being adjustable to suit curtains of different sizes.

A still further object is to provide means whereby the curtain adjusting device may be mounted upon the interior of the window frame or upon the exterior of the window frame as desired or may be mounted so that it may be adjusted up or down at the pleasure of the occupant of the car.

Other objects will appear in the course of the following description.

My invention is illustrated in the accompanying drawings wherein:—

Figure 1 is an inside face view of a door of an automobile having a window opening and showing my invention applied thereto with the curtain entirely raised;

Fig. 2 is a vertical sectional view through the window frame showing the curtain drawn downward so as to form an awning;

Fig. 3 is an enlarged sectional view through the support for the bow or curtain frame and through a portion of the bow;

Fig. 4 is a longitudinal sectional view through the transverse bar of the bow to show the manner in which the bow may be expanded;

Fig. 5 is an elevation looking toward the interior of the window frame, showing the manner of adjustably supporting the bow.

Referring to these drawings and particularly to Figures 1 and 2 it will be seen that I have illustrated the frame A as having the grooves *a* within which slides the usual window B. I have illustrated a spring roller 11 carrying a curtain 10, this roller being mounted upon the supporting brackets 12. Preferably the roller 11 will have the usual latches for the curtain removed therefrom so that the spring of the roller will all the time urge the curtain upward.

Mounted upon the jambs of the window frame are the supporting guides 13 which are illustrated as being disposed upon the inner faces of the jambs, these supporting members being annular in cross section so as to provide a guide for the tubular sleeve 22, the sleeve 22 having outwardly projecting ears 14, the outer faces of which are preferably radially corrugated. Confronting the ear 14 is the inner disk-like terminal end 16 of a tubular rod 15 and the portion 16 is rotatably mounted upon a pin or rivet 17 which extends through the ear 14 and surrounding this rod is a coiled spring 18 which urges the disk-like terminal member 16 against the ear 14. The confronting faces of the ear 14 and disk 16 are radially corrugated as at 19 so that the spring will cause these corrugations to interlock and thus the rod 15 will be held in any adjusted position upon the ear.

Coacting with the tubular rod sections 15 are the angular sections 20, see Figure 1, and the inwardly turned ends of these angular sections 20 are engaged in a tubular section 21, see Figure 4. Thus, the members 20 telescope within the section 21 and telescope within the section 15. The bow formed by the sections 15, 20 and 21 may thus be laterally expanded or contracted to suit windows or curtains 10 of different widths and the members 20 may be slidably adjusted within the members 15.

The guides 13 may be disposed either upon the front of the casing or upon the inner face thereof as desired though preferably

they will be disposed upon the inner face. The tubular sleeve 22 is adapted to slide vertically upon a vertical rod 13 whose upper and lower ends are angularly bent as at 23 and attached to the window casing. Thus, the bow formed of the members 15, 20 and 21 may be raised or lowered upon the rod 13.

In the use of this device the free end of 10 the curtain 10 is engaged with the cross piece of the bow in any suitable manner. The bow may be turned outward through the window openings when the window B is down and will thus draw the curtain outward and downward to the position shown in Figure 2, or the bow may be turned still further downward and the sections 20 forced out of the sections 15 so that the curtain will extend downward and outward so as to 20 nearly or entirely shield the window space. If it be desired, the bow may be turned upward to a vertical position on the inside of the window casing, as shown in Figure 2 in dotted lines and in this case, of course, the window curtain will be entirely rolled up and the window opening will be unobstructed. When the bow is turned within the window casing, the window B may be raised. The bow may be turned downward to a 30 horizontal position at right angles to the window frame or to any other desired angular position, or may be turned down so that it is vertically disposed and extends downward. In this latter position, assuming that the members 20 are withdrawn or 35 extended from the members 15, the curtain will close the entire window opening or the members 20 may be shifted inward into the members 15 to thus hold the lower edge of the curtain in spaced relation to the lower margin of the window opening. It will be 40 seen that a very large number of adjustments may be made of the window curtain and practically every possible adjustment of the window curtain may be secured. Thus, for instance, the light may be directed 45 downward toward the floor of the vehicle without the occupants of the vehicle being seen and without the light coming directly in through the window.

Obviously many minor changes might be made in the details of construction and arrangement of parts without departing from the spirit of the invention as defined in the 50 appended claim.

I claim:—

An awning for automobile window frames comprising a pair of brackets adapted to be mounted upon the inside face of the window frame at the upper end thereof, a spring roller mounted upon said brackets, a window shade carried by the spring roller, and approximately U-shaped bow including telescopic elements engaged with the free margin of the window shade, each element hav-

ing an angularly extending arm, a pair of vertical guides adapted to be mounted on the inside face of the window frame, brackets adapted to be slidably mounted upon said vertical guides thereof and having tubular portions in which the angular arms have telescopic engagement, the tubular elements being rotatably mounted upon said brackets, and means for holding the tubular elements in any angularly adjusted position, comprising opposed disk like members, one having teeth and the other having notches in which the teeth engage, the teeth and notches being concentric to the common center of the disk-like members and pivot pins passing through the disk-like members and having springs forcing the disk-like members together whereby said tubular elements are mounted for oscillation upon said brackets into a position projecting out through the window from the inside thereof or to a position entirely on the inside of said window, the tubular elements and the arms together having, when extended, a length equal to the distance between the brackets supporting the tubular elements and the top and bottom of the window.

In testimony whereof I hereunto affix my signature.

WILLIAM H. PEADEN.
